UNITED STATES PATENT OFFICE.

DAN F. DALTON, OF WATERBURY, ASSIGNOR TO JOSEPH C. HAMMOND, JR.,
OF ROCKVILLE, AND THEODORE E. KING, OF WESTPORT, CONN.

SHOE-CLASP.

SPECIFICATION forming part of Letters Patent No. 361,993, dated April 26, 1887.

Application filed May 18, 1885. Serial No. 165,787. (No model.)

To all whom it may concern:

Be it known that I, DAN F. DALTON, of Waterbury, in the county of New Haven and State of Connecticut, have invented certain new and useful Improvements in Shoe-Clasps, of which the following is a description, reference being had to the accompanying drawings, wherein—

Figure 1 is a perspective view of one form 10 of my improved clasp, showing its method of operation. Fig. 2 is a view, in central longitudinal section, of the parts engaged. Fig. 3 is a perspective view of an alternate form of tongue. Fig. 4 is a perspective view of an 15 alternate form of tongue-plate.

The object of my invention is to provide a buckle or clasp that is cheap in construction and efficient in operation, and which may be used on articles of wearing-apparel, but which 20 is more particularly adapted for use on overshoes.

It consists in a tongue pivotally connected to a plate or like support, and having on the lower side a hook or like device for engaging 25 loops or projections in a catch-plate, and above this a longer arm extending in position to serve as a means for moving the tongue to fasten or unfasten the device, and in the combination of the several parts, as more particularly herein- 30 after described.

In the accompanying drawings, the letter *a* denotes the tongue of a buckle or clasp which is formed from a piece of sheet metal folded back upon itself to form a pivot-socket, *b*, with 35 a down-turned and hook-shaped arm, *a'*, on the underneath part of the tongue, and the arm *a''* extending above and beyond the lower arm. This tongue *a* is pivotally connected to the tongue-plate *c*, which is preferably of metal 40 cut or stamped to shape by passing the tongue through the loop *c'* in the tongue-plate and folding it over and inclosing the cross-bar on the plate which serves as the pivot for the tongue. The catch-plate *d* is of ordinary construction, preferably struck from metal, with 45 the several openings *d'*, into any one of which the hook-shaped arm *a'* is thrust by pushing down upon the lever-arm *a''* of the tongue, as illustrated in Fig. 1.

The several parts of the device, when they 50 are engaged, occupy the relative position substantially as shown in the cross-sectional view in Fig. 2, and the tongue may be unclasped or disengaged by catching hold of the end of the lever-arm *a''* of the tongue, and by lifting it 55 and pulling the hook-shaped arm out of the opening in the catch-plate.

The tongue may be pivotally connected to the plate by forming the tongue-blank with projecting trunnions integral with it, as illustrated in Fig. 3, and forming the sockets in the tongue-plate by turning back the projections so that they may be closed down upon the trunnions.

It is obvious that there are forms of tongue-plate or equivalent means for supporting the tongue and connecting it to an article of wearing-apparel which may be used without departing from the main feature of my improvement, which consists in the pivotally-supported tongue having the hook-shaped arm or equivalent means for engaging the catch-plate and the projecting lever-arm which serves as the means for disengaging or engaging the parts.

The several parts of my improved clasp are 75 simple in form, and may be quickly and cheaply made and assembled.

I claim as my invention—

1. In a buckle or clasp, the tongue-plate 80 with its pivot-bearings, in combination with the pivotally-supported tongue *a*, having below the pivot the hook-shaped engaging-arm, and above the pivot the forward-extending lever-arm, all substantially as described.

2. In combination with the tongue-plate having a pivot-bar, the pivotally-supported tongue *a*, having below the pivot the hook-shaped arm *a'* and above the pivot the forward-extending lever-arm *a''*, and a catch- 85 90 plate, *d*, all substantially as described.

DAN F. DALTON.
